(57) **CLAIM**

The ornamental design for a disk holder, as shown and described.

DESCRIPTION

FIG. 1 is a perspective view of the disk holder of the present invention;

FIG. 2 is a top plan view of the disk holder of the present invention;

FIG. 3 is a front view of the disk holder of the present invention;

FIG. 4 is a bottom view of the disk holder of the present invention;

FIG. 5 is a back view of the disk holder of the present invention;

FIG. 6 is a right side view of the disk holder of the present invention; and,

FIG. 7 is a left side view of the disk holder of the present invention.

The broken line illustration of the tiggon mark and logo are shown in broken lines for illustrative purposes only and form no part of the claimed design.
